UNITED STATES PATENT OFFICE.

WILLIAM J. WOLFF, OF NEW YORK, N. Y., ASSIGNOR TO MEYER ROTHSCHILD AND RICHARD KUNO, OF NEW YORK, N. Y.

DESIGN FOR A BUTTON.

No. 39,395.

Specification for Design.

Patented July 7, 1908.

Application filed May 9, 1908. Serial No. 431,989. Term of patent 7 years.

To all whom it may concern:

Be it known that I, WILLIAM J. WOLFF, a citizen of the United States, residing in New York, in the borough of Brooklyn, county of Kings, and State of New York, have invented a new, original, and ornamental Design for Buttons, of which the following is a specification, reference being had to the accompanying drawings, forming part thereof, of which—

Figure 1 shows a plan view, and Fig. 2 a side view.

I claim—

The ornamental design for a button, as shown.

WILLIAM J. WOLFF.
